SWITCHING APPARATUS FOR ELECTRICALLY COUNTING RAPID RECIPROCATING MOVEMENTS

Robert Blomerius, Berlin-Frohnau, Germany, assignor to Rheinmetall-Borsig Aktiengesellschaft, Dusseldorf, Germany, a corporation of Germany

Application November 26, 1937, Serial No. 176,741
In Germany December 7, 1936

3 Claims. (Cl. 89—1)

For counting the number of shots fired by automatic guns, purely mechanical transmission mechanisms have not proved satisfactory. It has been demonstrated that with the high firing velocity of automatic guns, the action of such 5 mechanical transmission mechanisms is too sluggish to effect the acceleration of the driving mechanism necessary for the operation of the counter within the interval between successive shots. Moreover, mechanical transmission to 10 distant points has proved to be too troublesome.

Attempts have heretofore been made to utilize electrical means for operating counting devices. In such attempts a contact was closed 15 by a part of the gun which moved during the firing of a shot, and this contact closed the operating circuit of the counter. This was not a practicable method because the time during which the contact was effective was much shorter than was necessary for the operation of the 20 counter.

For this reason the present invention seeks to prolong the operative period in which the contact controlling the circuit is effective, in order 25 that sufficient time may be available for the moving gun part to transmit motion to the counter, said gun part moving in synchronism with the shot.

According to this invention when a shot 30 is fired and when a part of a recoiling gun reaches its rear end position the circuits for both a lamp and a counting device will be closed. The circuits of the counter are however prevented from being restored to its normal inoperative 35 condition during the return or forward movement of the gun part, by a locking device which latter is not released until the moving gun part has fully returned to its forward end position.

The accompanying drawing is a longitudinal section of a device, employed to count the shots 40 fired in an automatic gun in accordance with the present invention.

A housing *a*, which is screwed on to the gun casing, contains impact levers *b* and *b*₁ mounted in slots *a*₁ and *a*₂. A pressure rod *b*₃ is inserted 45 in a longitudinal boring in the housing *a* and an extension *b*₄ of the rod projects into a boring *c*₁ in a connecting rod *c*. The rod *b*₃ is biased to its position of rest by a compression spring *b*₅.

The connecting rod *c* has two notches *c*₂ and 50 *c*₃ arranged one behind the other, with which notches a spring-pressed pawl or latch *c*₄ operates. The rod *c* also carries a push member or abutment *c*₅ of insulating material and is secured against rotation by a pin *a*₃ which pro-

jects through a longitudinal slot *c*₆ in the connecting rod.

Electrical contacts *d*₁ and *d*₂ are mounted on an insulating member *d*, carried on the housing *a*, and are electrically connected with insulated 5 leads *d*₃ and *d*₄.

In the longitudinal boring in the housing *a* there is further inserted a pressure rod *e*, of which an extension *e*₁ projects into a boring in the connecting rod *c*. The rod *e* is prevented 10 from rotating by a pin *a*₄ projecting through a slot *e*₂ in the rod, and carries a push member or abutment *e*₃ of insulating material. The rod is biased to its position of rest by a compression spring *e*₄ which bears against a shoulder *e*₅ of 15 the housing *a*.

Two flexible contacts *f*₁ and *f*₂ are mounted in an insulating member *f* on the housing *a* and are electrically connected with insulated leafs *f*₃ and *f*₄. The lead *d*₃ is connected with the lead *f*₃ 20 which connects with a terminal *f*₅, while the leads *d*₄ and *f*₄ connect with the terminals *d*₅ and *f*₆ respectively. The terminals are preferably mounted in a junction box *d*₆. The counting device *g* is inserted between the terminals *d*₅ 25 and *f*₅, and a glow lamp *g*₁ is connected across terminals *f*₅ and *d*₆, both being supplied with electrical energy by a source of current *g*₂.

The mode of operation is as follows:

At the end of the recoil, a projection *V* on 30 the gun breech block impacts on contacts with the impact lever *b*₁, which then pushes the rods *e* and *c* forwards. This causes the abutment member *e*₃ to close contacts *f*₁ and *f*₂ and abutment member *c*₅ to close contacts *d*₁ and *d*₂. Since 35 the compression spring *e*₄ returns the rod *e* into its rest position immediately it has been released by the lever *b*₁, the contacts *f*₁—*f*₂, on firing a further shot, are immediately opened and this occurs before the lamp *g*₁ has time to glow. 40 If, however, the breech projection *V* remains in its rear position against the lever *b*₁, this fact is indicated by the glow lamp *g*₁ because its circuit remains closed by contacts *f*₁ and *f*₂. If, therefore, the lamp is not burning, the gunner 45 knows that he must cock before firing.

The connecting rod *c* is held by the pawl *c*₄, which, on the forward movement of the rod *e*, moves out of the notch *c*₂ into the notch *c*₃. The contacts *d*₁—*d*₂ are, therefore, held closed by 50 the abutment member *c*₅ and remain closed until the projection *V* of the breech block rocks the lever *b*. This rocking of the lever *b* by the projection *V* causes the rod *c* to return, under the influence of the rod *b*₃, into the position shown 55

in the drawing with the catch c_4 engaging in the notch c_2 , thus breaking the contacts d_1-d_2 . The time during which the circuit of the counter g is closed, is thus extended to the duration of the forward movement of the breech projection V , and is, therefore, sufficient to advance the counter g by one unit.

8 A further contact can obviously be provided, which could indicate by the lighting of a lamp 10 if the breech block rests in its forward position. This contact must be closed by the running of the projection V over the lever b , and must be broken when the projection again releases the lever.

15 I claim as my invention:

1. Switching apparatus for counting the strokes of rapidly reciprocating bodies and more particularly recoiling machine guns, comprising a lamp circuit and a counter circuit, separate 20 contacts for each circuit and means for momentarily closing the lamp circuit when such body reaches the end of its recoil and simultaneously closing the counter circuit for the duration of the counter-recoil of said body, said means being 25 actuated by said reciprocating body.

2. An apparatus according to claim 1, in which

said circuit closing means consists of an axially movable actuating member provided with an abutment for each of said contacts, a rocking lever exteriorly mounted adjacent to each end of said member and a projection on said reciprocating body adapted to rock one of said levers respectively at each end of its reciprocating stroke, thereby displacing said member to make and break said contacts respectively. 5

3. An apparatus according to claim 1, in which 10 said circuit closing means consists of an axially movable actuating member provided with an abutment for each of said contacts, a rocking lever exteriorly mounted adjacent to each end of said member and a projection on said reciprocating body adapted to rock one of said levers respectively at each end of its reciprocating 15 stroke, thereby displacing said member to make and break said contacts respectively, said actuating member consisting of three aligned, interengaging rods, compression springs adapted 20 to push the end rods against said levers and a spring latch adapted to retain the central one of said rods in and out of engagement respectively with the contacts in said counter circuit. 25

ROBERT BLOMERIUS.
